UNITED STATES PATENT OFFICE.

FREDERICK S. PRESCOTT, OF MEREDITH, NEW HAMPSHIRE, ASSIGNOR TO
THE GOLD MEDAL SEWING MACHINE COMPANY, OF ORANGE, MASS.

ATTACHMENT FOR SEWING-MACHINE PRESSER-FEET.

SPECIFICATION forming part of Letters Patent No. 244,074, dated July 12, 1881.

Application filed April 7, 1881. (No model.)

To all whom it may concern:

Be it known that I, FREDERICK S. PRESCOTT, of Meredith, county of Belknap, State of New Hampshire, have invented a new and useful Improvement in Sewing-Machine Presser-Foot Attachments, of which the following description, in connection with the accompanying drawings, is a specification.

This invention in sewing-machines has for its object the production of an improved presser-foot attachment, whereby a piece of raw-edged or bias material may be folded at each edge and be laid upon a piping, or upon edging or lace interposed between the said folded strip and the material upon which the folded strip and piping, &c., are to be stitched.

Figure 1 represents, in perspective, the side and under portion of a presser-foot having a binder and guide attached to it in accordance with my invention; Fig. 2, a top view of Fig. 1; Fig. 3, a section of Fig. 2 on the dotted line $x x$, and Fig. 4 a diagram showing the class of work which my improved attachment is adapted to perform.

A is supposed to be a presser-foot of a shape commonly used on the "Home" and other shuttle sewing-machines, b being a slot for the passage of the needle.

In accordance with my invention I have combined with this presser-foot a double binder, B, it having two lips, $c c'$, adapted to receive a bias or raw-edged strip, d , (see Fig. 4,) of cloth, and turn its edges underneath, as therein shown, laying the said strip horizontally upon the top of a layer of cloth, e , which may be a dress-skirt or other garment. At the rear of this double binder is placed a guide, f , made as a loop, having a tongue, g , the edge of which terminates at the right of the needle-hole b . This guide

is adapted to receive in and about the tongue g a bias or raw-edged piece of material, h , and fold and deliver it between the turned edges of the strip d and the fabric e , as at the right of Fig. 4, the needle of the sewing-machine entering the said materials and stitching them together by a line of stitching, as at i . One edge having been stitched, as described, the fabric e may be reversed and the other edge of the folded strip d , that previously in the lip c' , may be thereafter placed in the control of the lip c and be guided to the needle, to be stitched to the fabric e , and with or without the intervention of a piping, h .

If it should be desired, a piece of edging, or lace, or fringe, as at l , (see left of Fig. 4,) may be placed between the fabric e and the folded edge of the strip d .

I am aware that a hemmer has been applied to a presser-foot, in connection with a guide, to deliver a piece of edging or folded material between the parts of the fabric forming a hem, the said fabric being turned upward and over about the edge of the edging.

I claim—

The presser-foot A and attached binder, having the lips $c c'$, combined with the guide, to receive and lay a piping or edging between the material rested upon the cloth-supporting bed and the downwardly and inwardly turned edge of the strip of material folded by the binder, substantially as described.

In testimony whereof I have signed my name to this specification in the presence of two subscribing witnesses.

FREDERICK S. PRESCOTT.
